INVENTOR
GEORGE A. PIERCE

BY *Walton Harrison,*
his ATTORNEY

UNITED STATES PATENT OFFICE.

GEORGE A. PIERCE, OF PHILADELPHIA, PENNSYLVANIA.

SIGNALING SYSTEM.

Application filed October 31, 1919. Serial No. 334,663.

To all whom it may concern:

Be it known that I, GEORGE A. PIERCE, a citizen of the United States, residing at Philadelphia, in the county of Philadelphia and State of Pennsylvania, have invented 5 certain new and useful Improvements in Signaling Systems, of which the following is a full, clear, and concise description.

My invention relates to signaling systems, 10 and more especially to such annunciator systems as employ a number of manually operated circuit closers, such as push-buttons or keys, and a number of indicators, all of these parts being so arranged that an operator 15 at any station may readily transmit a signal to any other station of the system.

In annunciator systems of the kind just mentioned it is rather difficult to avoid complication in wiring, owing to the number 20 and diversity of the electrical functions to be performed. If too many wires are used the system becomes troublesome and expensive. If only a few wires are used it usually happens that each wire must perform more 25 than a single function and it becomes a difficult matter to keep these functions distinct.

One great difficulty with many of the systems heretofore in use is in preventing a given signal, intended for a particular station only, from producing undesirable effects 30 at other stations. A very common instance is that a signal intended to actuate an indicator at one station will in doing so actuate also an indicator at some other station.

In some instances use has been made of 35 intercommunicating signaling circuits, in which the distribution of the currents used for signaling is localized by apportioning the resistance of different portions of the 40 circuits. In practice, however, it has been found difficult to properly localize the action of the currents in this manner, owing to the fact that it calls for great refinement in apportioning the resistance of different portions 45 of the circuit. The result has been, therefore, that undesirable currents would manage to find their way into portions of the wiring where they did not belong, the net result being false signals and unnecessary waste of power. The currents thus undesirably straying off into circuits and parts 50 of circuits to which they do not belong have more or less of a vagrant character and are popularly known as "sneak" currents. An

important feature of my invention is to prevent these currents. This I do by so arranging the wiring as to close positively every path through which the energizing currents can pass, except the particular portions of the wiring intended to be energized. 55

In carrying out this idea, I find it convenient to employ, at each station, a plurality of relays, each having the function of an indicator, each relay being controllable from a particular station with which it is associated, each station having a bell or other audible signal located in and controllable by a local circuit common to all of the relays in the group at the station where this bell is located. By this arrangement, at any particular station, one of the relays serving as an indicator can perform its function and the bell or other audible signal at that station can be energized, without the possibility of affecting any other relay, either at 70 that station or at any other station. 75

Reference is made to the accompanying drawing forming a part of this specification and in which reference numerals indicate like parts throughout all of the figures. 80

Figure 1 is a diagram showing my system as used with three intercommunicating stations.

Figure 2 is a fragmentary diagram showing different connections for the local circuit 85 than those opposing in Figure 1.

Figure 3 is a fragmentary diagram showing the connections for the local circuit as different from those appearing in the other figures. 90

I will first describe the structure and operation of the mechanism shown in Figure 1.

The stations, three in number, are designated respectively as, station No. 1, station No. 2, and station No. 3, and, generally speaking, the mechanisms used at the respective stations are substantially alike, so that only one need be described in detail. 95

Located at each station is a bell 4 and two indicator magnets 5, 6, provided with armatures 7, 8, having the form of hooks and sustaining contact bars 9, 10, in such manner as to readily drop these bars when energized for this purpose. Each station is further provided with a circuit closer 11, having the form of a key or push-button and provided with contact members 12 and 13. Each station is also provided with another circuit 100

closer 14, similar to the one just described, and having contact members 15 and 16. The contact bar 9 is essentially a shutter and is provided with a legend 1, 2, or 3, as the case 5 may be, which is for the purpose of indicating the particular station from which it is controlled. Below the contact bar 9 are two contact buttons 17 and 18, through which a circuit is closed by the dropping of the 10 contact bar. The contact bar 10 is similar in construction and action to the contact bar 9, with the exception that any particular station the contact bar 10 bears a different legend from that borne by the contact bar 15 9, as the two contact bars just mentioned are controlled from different stations. Below the contact bar 10 are two contact buttons 19, 20, through which a circuit is closed whenever the contact bar drops. 20 Feed wires are shown at 21, 22, and are used for supplying electric current to the system. Connected with the feed wire 22 is a wire 23, and connected with this wire is a wire 24 leading to station No. 1, and then 25 connected to the contact member 16. From the contact member 16 a wire 25 leads to the contact member 13. A wire 26 is connected to the contact member 15, and leads therefrom to the magnet 6 of that station. A wire 27 is connected to the contact member 12 and is connected to the magnet 5. A wire 28 is connected with the feed wire 21 and is also connected with a wire 29 which leads to the magnet 6. A wire 30 is connected to the wires 28 and 29, and is also connected to a wire 31 leading to the magnet 5. A wire 32 is connected to the wires 30 and 31 and also to the bell 4. Connected with this bell is a wire 33 which is also connected to a wire 34, leading to the contact member 20. A wire 35 is connected with the wires 33 and 34, and leads therefrom to the contact button 18. A wire 36 is connected with the contact button 17 and with 40 a wire 37, the latter being connected with the contact button 19. A wire 38 is connected with the wires 36 and 37 and also with the wires 23 and 24. A wire 39 leads from the circuit closer 11 to station No. 2 45 and is there connected to the circuit closer 11 of that station. A wire 40 leads from the circuit closer 14 at station No. 1 to the circuit closer 14 at station No. 2. Connected with the feed wire 22 and with the wire 23 50 is a wire 41, and connected with the wire last mentioned is a wire 42 leading to station No. 2. Connected with this wire 42 is a wire 43 leading to the contact button 19 at station No. 2. Connected to the wires 42 55 and 43 is a wire 44 which leads to the contact button 17 at this station. The adjacent contact button 18 is connected to a wire 45, and connected to the wire 45 is a wire 46 leading to the contact button 20. The wires 45 and 46 are connected to a wire 47 which 60 leads to the bell 4 of this station. From this bell a wire 48 leads to a wire 49 which is connected to the magnet 5. A wire 50 is connected to the wires 48 and 49 and is also connected to the wire 51, the latter leading 70 to the magnet 6 at this station. A wire 52 leads from this magnet to the contact member 15 at this station. The adjacent contact member 16 is connected to a wire 53, this wire being connected to a wire 54 which 75 leads to the adjacent contact member 13. From the contact member 12, a wire 55 leads to the magnet 5. The wire 56 is connected to the circuit closer 14 of this station, and leads therefrom to station No. 3, where it is 80 connected with the circuit closer 11. Connected with the wires 50 and 51 at station No. 2 is a wire 57. This wire is connected to a wire 58, the latter leading to the feed wire 21 and also to the wire 28. Connected with 85 the wires 57 and 58 is a wire 59 leading to station No. 3 and there connected with a wire 60 which leads to the magnet 6 of that station. A wire 61 is connected to the wires 59 and 60 and also to a wire 62, 90 the latter leading to the magnet 5. A wire 63 is connected with the wires 61 and 62, and leads therefrom to the bell 4 of station No. 3. Connected with this bell is a wire 64, and to this wire is joined a wire 65 leading to the contact button 20 of this station. A wire 66 is connected with the wires 64 and 65, and leads therefrom to the contact button 18. A wire 67 is connected with the adjacent contact button 17, and a wire 68 is 95 connected with the wire 67 and also with the contact button 19 at this station. The wires 67 and 68 are connected to a wire 69, and connected with the wire 69 is a wire 70. From the latter, a short wire 71 extends to 100 the contact member 16. A wire 72 is connected to the wires 70 and 71, and leads therefrom to the contact member 13. A wire 73 leads from the contact member 12 at this station to the indicator magnet 5 at 110 the same station. A wire 74 leads from the indicator magnet 6 at this station to the contact member 15 at the same station. A wire 41^a is connected with the wires 41 and 42, and with a wire 41^b which is connected with the wires 53 and 54. A wire 41^c is connected with the wires 41^a and 41^b, and with the wires 69 and 70. 115

All of the movable parts appear in their respective normal positions, the apparatus 120 as a whole being shown as idle.

The operation of my device as shown in Figure 1 is as follows:

Suppose the operator at station No. 1 wishes to call the operator at station No. 2. 125 For this purpose, he actuates by hand the circuit closer 11 at station No. 1. This closes a circuit, which may be traced as follows: feed wire 22, wires 23, 24 and 25, contact button 13, circuit closer 11, wire 39 130

to station No. 2, circuit closer 11 of this station, wire 55, magnet 5 of station No. 2, wires 49, 50, 57 and 58, feed wire 21 to source of supply (not shown), and thence 5 back to feed wire 22. This circuit energizes the magnet 5 at station No. 2 and causes it to attract its armature 7, thus releasing the contact bar 9 which drops upon the contact buttons 17 and 18. Since this 10 contact bar carries the legend 1, such legend is practically displayed by the dropping of the contact bar. Thus a visual signal is displayed for the purpose of calling the attention of the operator at this station to the 15 fact that the operator at station No. 1 is calling.

The dropping of the contact bar 9 at station No. 2 closes a circuit which may be traced as follows: feed wire 22, wires 41, 42 20 and 44, contact button 17, contact bar 9, contact button 18, wires 45 and 47, bell 4 at station No. 2, wires 48, 50, 57 and 58, feed wire 21 to source of electrical supply (not shown), and thence back to feed wire 22. 25 This circuit rings the bell 4 at station No. 2, and in this manner the operator at station No. 2 is apprised, by an audible signal that a call is being made and the visual signal above described indicates by the display of 30 the legend that station No. 1 is the station calling.

It will be noted that the magnet 5 together with its armature 7 and contact bar 9, the latter carrying the legend 1, collectively 35 constitute a relay having the function of an indicator. It will also be noted that the dropping of the contact bar 9 of the relay just described controls what is essentially a local circuit, including the bell 4 at 40 station No. 2.

The operator at station No. 2, after noting the signal, restores the contact bar 9 at this station to its normal position, and this he can do in any conventional manner.

45 If he wishes to repeat the signal, or in other words, wishes to apprise the operator at station No. 1 that the signal transmitted to station No. 2 has been noted, the operator at the station last mentioned can transmit to station No. 1 a signal for that purpose.

It will be observed that while the circuit closer 11 at station No. 1 is depressed the circuit closer 11 at station No. 2 is up. If, 55 however, it should happen that both of these circuit closers are depressed at exactly the same instant, no indication is made because no circuit is closed, and if one of the circuit closers be released before the other, 60 the one first released will not cause any indication to be made. However, no trouble is likely to arise from the conditions just mentioned. In the first place an operator, in actuating a circuit closer, usually presses 65 upon it a number of times in rapid suc-

cession. In the second place he will repeat the call two or three times if he fails to get a signal.

Suppose, next, that the operator at station No. 1 wishes to call the operator at station 70 No. 3. For this purpose, the operator at station No. 1 actuates the circuit closer 14 at his station, thereby completing a circuit as follows: feed wire 22, wires 23, 24, contact button 16, circuit closer 14, wire 40 to station No. 3, circuit closer 14 at that station, wire 74, magnet 6 at station No. 3, wires 60, 59 and 58, feed wire 21 to source of supply (not shown), and thence back to feed wire 22. This circuit energizes the 80 magnet 6 at station No. 3 so that the armature 8 of this magnet is caused to disengage the adjacent contact bar 10, bearing the legend, 1, and causes this contact bar in dropping to display the legend just mentioned and to engage the contact buttons 19 and 20.

A circuit is thus completed, and may be traced as follows: feed wire 22, wires 41, 41^a, 41^c, 69 and 68, contact button 19, contact bar 10, contact button 20, wires 65 and 64, bell 4 at station No. 3, wires 63 and 61, wires 59 and 58, feed wire 21 to source of supply (not shown), and thence back to feed wire 22. This circuit rings the bell 4 95 at station No. 3, and thus produces an audible signal for the attention of the operator at station No. 3. Having noted the signal, he proceeds as above described with reference to the operator at station No. 2. 100

All circuits, except those above described as completed in the manner and for the purposes stated, remain open. It follows, therefore, that while the operator at either station can produce a visual signal at either of the other stations as desired, and can supplement the visual signal by an audible signal, there is no possibility of any undesirable signal, either audible or visual, being made at any other station than the one for which the circuit is closed. Each circuit employed is clean-cut and sharply defined, and none of the circuits are controllable by gradually changing or uncertain resistances or inductances. No vagrant or 110 "sneak" currents can creep into the system, and the wiring is quite simple for the results accomplished. Neither the circuits controlling the visual signals nor those controlling the audible signals have any haphazard connections of such character as would be likely to form a ground-work for undesirable vagrant currents. 120

It will be noted that the relays, in closing the bell circuits, quite materially shorten the 125 paths through which the currents used in signalling can follow. This fact is of importance in that by shortening some of the circuits, or at least by shortening the circuits used for some purposes, I not only simplify 130

the wiring but reduce still further, if possible, the chances for vagrant or "sneak" currents to make their appearance.

With the parts constructed and arranged as shown in Figure 1, whenever any one of the bell circuits is energized the bell continues to ring until the relay controlling the bell circuit is reset.

In instances where the continuous ringing of the bell is objectionable, I may arrange each bell circuit and construct the various parts associated therewith as shown in Figure 2 or in Figure 3, as the case may be.

I will now describe the mechanism shown in Figure 2.

A drop shutter appears at 75; and is normally supported by a hook 76. This hook is made of soft iron, and constitutes an armature for a magnet 77. This magnet is provided with two windings 78, 79. Connected with the winding 78 are two wires 80, 81. Two wires 82, 83, lead from the winding 79 to the winding 84, with which a relay 85 is provided.

The relay 85 is also provided with an armature 86 and with a contact 87, which is normally open. A wire 88 leads from the contact 87 to the bell, which appears at 4. Connected with this bell is a wire 89, which is also connected with the wire 80 and with a wire 90. A wire 91 is connected with the armature 86 and with a contact member 13 of the circuit closer 11 shown in this figure. A wire 92 is connected with the contact member 13 and with the wire 91. A wire 93 is connected with the circuit closer 11.

Whenever the magnet 77 is energized as hereinafter described the hook 76, serving as an armature, is attracted and the shutter 75 drops and thus displays a visual signal, which remains continuously displayed until the shutter is reset, or restored to its normal position.

Each time the magnet 77 is thus energized by its winding 78, the winding 79 is energized inductively, and whenever this occurs a current is generated in the winding 79 and flows through the winding 84, in a circuit which may be traced as follows:

Winding 79, wire 82, winding 84, and wire 83, back to winding 79. This energizes the relay 85, so that the armature 86 is attracted, and thus closes a circuit through the bell 14, the bell being thus energized for an instant only, and consequently making only a single stroke.

The group of mechanism shown in Figure 2 may as a whole be substituted bodily for a corresponding group of mechanism shown in Figure 1. For instance at station No. 1 the magnet 5 and the bell circuit controlled thereby may be supplanted by the mechanism shown in Figure 2, by merely disconnecting them from the wires 29, 39 and 25, and connecting these wires, re-

spectively with the wires 90, 93 and 92 of Figure 2.

In the form shown in Figure 3 a wire 93 is connected with two wires 94 and 95, the wire 94 leading to a relay 96 and the wire 95 leading to the bell 4. A wire 97 leads from this bell to a contact 98, controllable by the relay armature 99. Connected with this armature is a wire 100. A wire 101 is connected to the relay 96. The relay is provided with a drop shutter 102, which is controllable by a hook armature 103.

With the form shown in Figure 3, a visual signal may be made by the dropping of the shutter, and an audible signal may be made by the ringing of the bell. Since, however, the bell only rings while the relay 96 remains energized, the duration of the ringing is always short.

The mechanism shown in Figure 3 is easily substituted for corresponding parts shown in Figure 1. For instance in order to substitute this mechanism instead of the magnet 5 and parts controllable thereby at station No. 1, the wires 93 and 100 are merely substituted for the wires 30 and 36 at that station.

Except as otherwise indicated, the structure and action of the various parts shown in Figures 2 and 3 is the same as that of corresponding parts shown in Figure 1.

With the mechanism shown in Figure 2, the drop shutter 75 may, if desired, be used exclusively of the wiring shown at the left of the figure. In other words the operator can use either a visual signal or both a visual signal and an audible signal, or both, as he may desire.

This is also true of the mechanism shown in Figure 3. That is to say the operator can rely upon the drop shutter or upon both the drop shutter and the single ring bell, as desired.

I do not limit myself to the precise mechanism shown as variations may be made therefrom without departing from my invention, which is commensurate with my claims.

I claim:

1. In a signaling system having a plurality of intercommunicating stations at least two in number, the combination of a plurality of circuit closers and relays, each station having one of said circuit closers for each of the other stations and also having one of said relays for each of the other stations, and circuit connections between said stations including a single local circuit controlled by each of said relays at the particular station where this relay is located, a single pair of signaling wires leading from each station to each of the other stations, and connections leading to said circuit closers said relays and said local circuits, from a single source of electricity.

2. A signaling system comprising a number of circuit closers located at separate stations, a plurality of relays located at each of said stations, an electrically operated signaling member located at each of said stations, a single source of electricity, wiring from said source of electricity to said circuit closers and thence to said relays for enabling each circuit closer to control a particular relay with which it is associated, and connections from said wiring and from all of said relays to said electrically operated signaling member and to said single source of electricity for enabling any one of said relays, when energized, to control the circuit of the electrically operated signaling member at the same station.

3. A signaling system comprising a plurality of relays located at a station, a single source of electricity common to all of said relays, wiring from said source of electricity to said relays for the purpose of enabling said relays to be energized independently of each other from said source of electricity, an electrically operated signaling member common to all of said relays, and connections from said wiring to said electrically operated signaling member and to said single source of electricity for enabling any one of said relays, when energized, to control the circuit of said electrically operated signaling member.

4. A signaling system comprising a number of circuit closers located at separate stations, a plurality of relays located at said separate stations, a source of electricity common to all of said circuit closers and said relays, wiring from each circuit closer to a relay located at some one of the other stations than the one at which said last men-

tioned circuit closer is located, said wiring being also connected to said source of electricity for enabling said source of electricity, under control of any one of said circuit closers, to energize the particular relay with which said last mentioned circuit closer is connected, an electrically operated signaling member located at each station and having a circuit controllable by each of the relays at that same station, and connections from said electrically operated signaling member to said last mentioned relays and to said circuits controllable thereby, for enabling said source of electricity, under control of any one of said last mentioned relays, to energize said electrically operated signaling member at the station where the relay is located.

5. A signaling system comprising a number of circuit closers located at different stations and a number of relays also located at said different stations, each station having a relay and a circuit closer for each of the other stations, a source of electricity, wiring connected with said source of electricity and with said circuit closers and relays, for enabling each circuit closer to control a relay at some other station than the one at which said last mentioned circuit closer is located, an electrically operated signaling member located at each station, and connections from the electrically operated signaling member at each station to all of the relays located at the same station and also to said wiring, for the purpose of enabling said source of electricity, under control of a circuit closer and a relay, to control the circuit of said electrically operated signaling member.

GEORGE A. PIERCE.
